(57) **CLAIM**

The ornamental design for a wash station, substantially as shown.

DESCRIPTION

FIG. 1 is a top, front, right perspective view of a wash station showing a first embodiment of our design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a top, front, right perspective view showing an alternate position of the first embodiment.

The broken lines illustrate portions of the wash station that form no part of the claimed design.
